SELF-CLEANING COMB

Lester K. Franklin, Los Angeles, Calif.

Application June 21, 1950, Serial No. 169,360

2 Claims. (Cl. 132—28)

1

This invention relates to new and useful improvements in combs for the hair and more particularly to a self-cleaning comb.

One difficulty encountered in the use of a hair comb is to maintain the same in a clean condition. Due to the close spacing of the teeth of an ordinary comb, hairs and other matter become lodged therebetween, particularly at the juncture of the teeth with the body or back of the comb. Removing such unwanted and unsanitary matter has proven to be an extremely vexing problem inasmuch as some sort of tool or implement must be inserted between each adjacent pair of teeth and the matter pried out of its lodging place. Further, extreme care must be exercised in the manipulation of the cleaning tool lest one or more of the somewhat delicate teeth of the comb be broken and the comb made worthless.

One object of the invention, therefore, is the provision of a comb embodying means for cleaning any collected matter from between all of the teeth thereof in one simple operation.

Another object of the invention is the provision of means adapted to be associated with existing combs for cleaning collected matter from between all of the teeth thereof in one simple operation.

A further object of the invention is to construct the said means so that all of the sides of each tooth are cleaned, not only the spaces between the teeth.

A still further object of the invention is to construct the said means so that the same is capable of being manufactured economically.

For further comprehension of the invention and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of the comb constructed in accordance with the present invention.

Fig. 2 is a view similar to Fig. 1 but illustrates the cleaning means in a partially removed position.

Fig. 3 is a perspective view of the cleaning means removed from the comb.

Fig. 4 is an enlarged sectional view on line 4—4 of Fig. 3.

Fig. 5 is a fragmentary bottom plan view of the cleaning means.

Fig. 6 is a sectional view on line 6—6 of Fig. 1.

Fig. 7 is a sectional view similar to Fig. 6, but illustrates a modified construction.

2

Fig. 8 is a view similar to Fig. 6 but illustrates another modified construction.

Fig. 9 is a view similar to Fig. 8 but illustrates the parts in another position.

5 Fig. 10 is another view similar to Fig. 6, but illustrating the comb constructed in accordance with a still further modification of the present invention.

10 The comb and associated cleaning means, according to the first form of the present invention illustrated in Figs. 1 to 6, includes a comb, back 10, from which projects a plurality of closely spaced teeth 11. At either end of the comb a wide guard tooth 12 projects from the back 10 in alignment with the teeth 11. Preferably the entire comb is molded of synthetic resin or plastic material.

15 Referring also to Fig. 6, it will be seen that the teeth 11 have their side edges parallel with one another for the greater part of the length of the teeth, and converge to form a somewhat flat point 13 at the face ends thereof; and, as in Fig. 6, the under edge 14 of back 10 between the teeth is rounded.

20 25 According to the invention there is provided a cleaning member 15 in the form of a channel piece whose base 16 is formed with a curvature to complement that of the under edge 14 of back 10 and whose side walls are slightly inclined toward one another, see particularly Fig. 4. Preferably member 15 is molded of the same material as the comb. The rounded base 16 of the channel member 15 is provided with a plurality of transverse slots 17, one for each of the teeth 11, and each extending from one side wall of the channel to the other. When the channel 15 is mounted in normal position on the comb, the base thereof, that is, the material between the slots 17, abuts the rounded under edge 14 of the back 10 between the teeth 11; and the side walls of the channel are held against the sides of back 10 by their own tension.

30 35 From Figs. 1 and 6, it will be noted that the upstanding side walls of the cleaning member 15 are shaped to complement the shape of the comb back 10 so that top and end edges of the side walls of the cleaning member will be flush with the top and end edges of the comb back. The free edges of the side walls of the cleaning member 15 are rounded, as shown in Fig. 6, to provide rounded corners at the top and ends of the comb when the cleaning member 15 is in position thereon.

40 45 50 55 In order to assure that the cleaning member 15 is set perfectly in normal position with the material between every pair of slots 17 in the base

thereof abutting the rounded under edge 14 of the back 10 between every pair of teeth 11, the inner faces of the side walls of member 15 are provided near either end with a rounded extrusion 18 for engagement with a complementary depression 20 in the comb back 10.

The construction is such that when the extrusions 18 of the cleaning member 15 are engaged in the depressions 20 the comb is utilized in the normal manner for dressing the hair. When the hair has been dressed the cleaning member 15 is moved from its Fig. 1 position through the position shown in Fig. 2 and finally free of the teeth 11 entirely, any hair or other matter lodged between the teeth 11 is removed. The member 15 then is cleaned by placing the same under a water tap or in any other manner and is replaced on the comb.

It is to be mentioned at this point that the invention contemplates the use of the cleaning member 15 with existing combs, the slots 17 in the base 16 thereof being made of the same size and spacing as are the teeth of such existing combs.

It may be desired to provide some guidance for the member 15 in its movements from the normal position shown in Fig. 1 to the partially removed position shown in Fig. 2, and beyond, so that the said member remains parallel with the back 10 of the comb. To this end the base 16^a of the member 15 may be made considerably thicker than described hereinbefore, see Fig. 7, so that the slots therein engage a greater portion of each of the teeth 11.

In that modification of the invention shown in Fig. 7, the side walls of the cleaning member 15 are stopped slightly short of the top edge of the comb back 10^a. However, the top edge of the comb back 10^a is formed with laterally extending shoulders 10^{aa} against which the top edges of the side walls of the cleaning member 15 abut when the cleaning member is properly positioned on the comb.

A further modified form of the invention has for its purpose also to clean the tapering ends of the side edges of the teeth 11. This form of the invention is illustrated in Figs. 8 and 9 wherein like parts are given the same reference numerals as hereinbefore with a prime added.

In this form of the invention the side walls of the channel cleaning member 15' are formed at their upper ends with points 21 which continue into upward angularly disposed cleaning surfaces 22.

The construction is such that when the cleaning member 15' is in normal position on the comb the side walls thereof are spaced angularly away from the back 10' of the comb by the points 21, see Fig. 8. However, as the member 15' has a cleaning movement imparted thereto, the points 21 scrape along the parallel side edges of the teeth 11' and clean the latter; and when the said points reach the tapering end portions 13' of the teeth 11' the angular cleaning surfaces 22, see Fig. 9, engage the tapering portions and clean them.

Again, the top edges of the side walls of the cleaning member 15' are stopped short of the top edge of the comb back 10' and that comb back is formed with laterally extending projections 10'' against which the top edges of the side walls are abutted, see Fig. 8.

In the further modification of the invention shown in Fig. 10, the side walls of the cleaning member 15^b are spaced a distance greater than

the major portion of the comb back 10^b. However, the top portion 10^{bb} of the comb back 10^b is thickened to occupy the full space between the adjacent faces of the side walls of the cleaning member 15^b, with the top edges of those side walls being flush with the top edge of the comb back 10^b.

At the junction of the side walls of the cleaning member 15^b with the base wall 16^b thereof, there are formed upwardly and inwardly directed scraping portions 25 for scraping the outer sides of the teeth 11 of the comb as the cleaning member 15^b is being removed from the comb. The scraping portions 25 can be formed as one-piece along the entire length of the cleaning member 15^b.

In other respects, the forms of the invention shown in Figs. 7 to 10 are similar to that illustrated and described in connection with 1 to 6 and like reference numerals are used to identify like parts.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A self cleaning comb comprising a comb back having a series of closely spaced teeth projecting therefrom, and a cleaning member in the form of a channel piece having side walls to engage the side faces of the comb back and a base with a slot therein for each said tooth to project through, said side walls being spaced adjacent said base from the adjacent sides of said comb back, and scraping portions formed within said cleaning member at the junction of said side walls with said base for scraping the outer sides of the teeth as the cleaning member is removed from the comb.

2. A self cleaning comb comprising a comb back having a series of closely spaced teeth projecting therefrom, and a cleaning member in the form of a channel piece having side walls to engage the side faces of the comb back and a base with a slot therein for each said tooth to project through, said side walls being spaced adjacent said base from the adjacent sides of said comb back, and a longitudinal scraping member at the junction of each of said walls with said base and extending along the length of said cleaning member for scraping the outer sides of the teeth as the cleaning member is removed from the comb.

LESTER K. FRANKLIN.
